Primary Examiner — Antoine Duval Davis(74) *Attorney, Agent, or Firm* — Chun-Ming Shih; lanway ipr services(57) **CLAIM**

The ornamental design for a gas detector as shown and described.

DESCRIPTION

FIG. 1 is a perspective view of a gas detector showing the new design;

FIG. 2 is another perspective view thereof;

FIG. 3 is a front view thereof;

FIG. 4 is a back view thereof;

FIG. 5 is a left side elevational view thereof;

FIG. 6 is a right side elevational view thereof;

FIG. 7 is a top view thereof;

FIG. 8 is a bottom view thereof; and;

FIG. 9 is an enlarged detail view taken from the encircled area 9 in FIG. 1.

The broken lines shown in the figures are for the purpose of illustrating portions of the gas detector and form no part of the claimed design.
